ELECTRIC HANUKKAH LAMP

Ernest Goldberg, New York, N.Y.

Application August 13, 1958, Serial No. 52,199

Term of patent 14 years

(Cl. D48—20)

The figure is a perspective view of an electric Hanukkah lamp embodying my new design, both sides being the same.

The essential features of my design reside in the portions shown in full lines.

The cord is shown broken away in part in the figure to indicate indeterminate length.

I claim:

The ornamental design for an electric Hanukkah lamp, as shown and described.
